GIRDLE

Clarke W. McKee, San Diego, Calif.

Application April 17, 1933, Serial No. 666,496

8 Claims.

(Cl. 2—41)

My invention relates to girdles, more particularly to girdles used as abdominal supports, and the objects of my invention are:

First, to provide a girdle which is so constructed that the tension is equalized throughout the width of the girdle dependent upon the pressure;

Second, to provide a girdle of this class in which a flexible fabric is reinforced by a strip on the exterior thereof which automatically equalizes so that if one portion of the strip is tightened so that it binds more than the other it is automatically equalized throughout the width of the girdle;

Third, to provide a girdle of this class in which the tension on the girdle is practically equalized in proportion to the pressure exerted against it on its full width and on its full length;

Fourth, to provide a girdle of this class which assumes an equal pressure on the body over its whole area dependent upon the pressure against the girdle at all points;

Fifth, to provide a girdle of this class which is very comfortable to wear though effective and efficient in operation; and

Sixth, to provide a girdle of this class which is very simple and economical of construction, durable, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a perspective view showing the girdle complete in its preferred form buckled up ready for use; Fig. 2 is a side elevational view of the same extended and practically straight and unbuckled; Fig. 3 is a view similar to Fig. 1 showing the girdle in a slightly modified form; Fig. 4 is a view similar to Fig. 2 showing the girdle in the modified form shown in Fig. 3, and Fig. 5 is an enlarged sectional view through 5—5 of Fig. 4.

Similar characters of reference refer to similar parts and portions throughout the preferred form and throughout the modified form shown in the several views of the drawing.

The girdle in the preferred form consists of a piece of flexible material, preferably fabric, 1 which is wider at the front portion 1a and 1b and the back portion 1d, and slightly narrower at the

side portions 1c. It is supported in its position on the body by means of a single reinforcing and equalizing strip 2 preferably of strong fabric which serves as equalizer means. In the preferred form this strip consists of a single member which extends, as shown best in Fig. 2, from the upper end portion 2b through one side of the keeper 3, then through a slit 5a in the member 5 through one side of the buckle 6 which is provided with a loop member which sheaves the strip 2, then backwardly under the member 5 through the lower sides of the three keepers 4, and the keeper 3, and ends at 2b at the lower side.

Secured intermediate the two ends 2b is another strip 7 of similar material to that of the strip 2 which is secured to the middle of the member 1 at the one end reinforced by the keeper 3. At the opposite end are provided similar strips 8 on opposite sides of the strip 2 and secured to the member 1 and reinforced by the keeper 5. To the strips 8 are secured buckles 9 so that there are provided on the one end three buckles 6, 9, and 9. At the other end the ends of the strip 2 fit into the buckles 7, 2b and 2b.

It will be noted that the keepers 3, 4, and 5 support the strip 2 relatively to the member 1 in certain relation regardless of the position of the member 2 longitudinally so that the support of the strip 2 is distributed over the member 1 in the same relation regardless to the position of the strip 2.

In as much as this support 2 is a single member, if one end of the strip is buckled tighter than the other, the pressure will quickly equalize by the strip drawing through the members on the member 1 so that the pressure is equally distributed throughout the girdle at all times dependent upon the pressure against the same.

In the modified form shown in Figs. 3, 4, and 5 the fabric is composed of two portions 11 and 12 adapted to be connected at the front and back and adapted to overlap. This overlapping may vary considerably to provide for greater adjustment of the length of the girdle; the opposite ends of both strips being wider so that the shape when ready for use or in use is substantially the same as that shown in Fig. 1, being wide at 11a and 12b and 11b and narrow at 11c and 12c. In this modified structure, two main reinforcing and equalizing strips, designated 13 and 21, are used which serve as equalizer means.

Taking Fig. 4 the strip 13 starts at 13b extends through one side of the members 14 and 15, then through a double loop member 16 at 13a

which sheaves the strip, and back through the lower side of the keepers 15 and 14 and ending at 13b. The strip 21 starts at 21a where it is secured to the member 11 at its one end, then 5 through the upper side of the keeper 22, through the keeper 20 intermediate its sides, through the buckle 23 which sheaves the strip, as shown at 21b, then back through the keeper 20 intermediate its sides, then through the lower side of 10 the keeper 22, and secured to the end 11b of the member 11 at the lower side.

The loop member 16 is secured to the member 12 near the end 12b at the middle portion by means of a loop member 17 which is secured 15 on the opposite side of the member 12 at the end 12b passing through a slit 11d.

Secured to the extended end of the member 12 are strips 19 reinforced by the keeper 20 and on the ends of which are secured buckles 18 at 20 the upper and lower sides of the member 12. At the extended end of the member 11 is secured a strip 24 at the middle portion between the ends 13b of the strip 13 and reinforced by the keeper 14. The strip 24 is buckled in the buckle 23 and 25 the ends 13b of the strip 13 are buckled into the buckles 18, as shown best in Fig. 3 of the drawing. Thus this modification provides for similar flexibility to that shown in Fig. 1 but uses two general reinforcing strips instead of just one; 30 but having similar distribution and equalization of the opposing pressures and also providing for greater length adjustment because of the overlapping ends of the two main fabric girdle members instead of one.

35 It will be noted that in either of the structures shown in Figs. 1 and 2 or those shown in Figs. 3, 4 and 5, that if one of the strips is secured in the buckle tighter than the other there will be ready distribution and equalization of the pressure throughout the girdle because of the longitudinal movement of the strips through the keepers and buckles.

Though I have shown and described a particular construction, combination and arrangement 45 of parts and portions, and a certain modification thereof, I do not wish to be limited to this particular construction, combination and arrangement, nor to the modification, but desire to include in the scope of my invention the construction, combination and arrangement substantially as set forth in the appended claims.

Having thus described my invention, what I claim as new and desire to secure by Letters Patent is:

55 1. In a girdle of the class described, a main flexible girdle means, and a reinforcing and equalizing strip supported at its one end near one marginal side and near one end of said girdle means, said equalizing strip extending from said one end toward the longitudinal middle of said girdle means and shiftably connected at said middle then extending backwardly against itself and supported again near the other marginal side at said one end of the girdle means the ends of said strip extending past the end of said girdle, and means near the opposite marginal sides of the other end of said girdle means for securing the extended ends of said strip.

70 2. In a girdle of the class described, a main flexible girdle means, a plurality of transversely extending keeper members secured in spaced apart relation along said girdle means, a pair of marginally disposed buckles at one end of the girdle means, a centrally disposed strap secured 75 at the opposite end of the girdle means, a re-

inforcing and equalizing strip arranged with its middle portion shiftably supported at the longitudinal axis of the girdle means and extending therefrom through said keepers to said opposite end of the girdle means, the extremities of the equalizing strip being engageable with said buckles when the girdle means is looped, and means arranged to coact with said strap.

3. In a girdle of the class described, a main flexible girdle means, a plurality of transversely extending keeper members secured in spaced apart relation along said girdle means, a pair of marginally disposed buckles at one end of the girdle means, a centrally disposed strap secured at the opposite end of the girdle means, a reinforcing equalizer strip arranged with its middle portion shiftably supported at said one end of the girdle means between the buckles, and extending therefrom through said keepers to said opposite end of the girdle means, the extremities of the equalizer strip being engageable with said buckles when the girdle is looped, and means carried by the middle portion of the reinforcing and equalizer strip arranged to coact with said strap.

4. A girdle structure comprising, a girdle, a reinforcing and equalizing strip including a middle portion disposed at one end of the girdle, a pair of embracing portions extending longitudinally with the girdle and extreme portions at the remaining end of the girdle, a plurality of keeper means guiding the major parts of the embracing portions along the margins of the girdle, a pair of securing elements at the margins of the one end of the girdle, engageable with the extreme portions of the strip when the girdle is looped, a securing device between said securing elements and including a loop portion sheaving the middle portion of the strip, and means for attaching said securing device to said remaining end of the girdle.

5. A girdle comprising, a flexible band means adapted to encircle the waist of the wearer and having overlapping extremities, a pair of marginally disposed securing elements at one extremity of the band means, a securing device disposed between said securing elements, and incorporating a loop portion, a reinforcing and equalizing strip sheaved by its middle portion through said loop portion, said strip being doubled to form a pair of encircling portions adapted to embrace the band means, and having end portions protruding beyond the remaining extremity of the band means to cooperate with said securing elements, and a strap secured to said remaining end of the band means and engageable with said securing device to draw on said strip and equalize the tension between said encircling portions.

6. A girdle structure comprising, a girdle having relatively wide portions at the front and back of the wearer and narrowed portions at the sides of the wearer, a reinforcing and equalizing strip including a middle portion doubled against itself and disposed at one end of the girdle, embracing portions continuing therefrom in the same direction around the girdle, and having extreme portions at the remaining end of the girdle, a plurality of keeper means guiding the encircling portions along the margins of the girdle in conformity therewith, a pair of securing elements at the margins of the one end of the girdle, engageable with the extreme portions of the strip when the girdle is looped, a securing device between said securing elements and including a

loop portion sheaving the central portion of the strip, and means for attaching said securing device to said remaining end of the girdle.

7. A girdle structure comprising, a pair of complementary girdle members adapted to overlap at the front and back of the wearer, and being relatively wide at their overlapping portions and constricted at their intermediate portions, a strap at the one extremity of each girdle member, a sheaving loop carried by each strap, a reinforcing and equalizer strip connected by both its extremities to the remaining end of each girdle member sheaved at its middle portion through the loop of the other girdle member, one of the sheaving loops and the extremities of one of the reinforcing and equalizer strips being separable from the girdle members to permit splitting of the girdle structure.

8. In a girdle of the class described, a main flexible girdle means comprising a first and a second girdle member overlapping at their one ends and their other ends extended in opposite

directions, a plurality of traversing keeper members on said girdle members, a loop member at the overlapping end of the first girdle member, a first reinforcing and equalizing strip freely slideable by its middle portion in said loop member and arranged with its end portions extending through the keeper members of the second girdle member to and beyond its extended end, a second reinforcing and equalizing strip secured by both its ends to the overlapping end of the second girdle member and extending therefrom through the keeper members of the first girdle member to the extended end thereof, a buckle sheaved upon the middle portion of the second reinforcing and equalizer strip at the extended end of the first girdle member, a strap at the extended end of the second girdle member arranged to coact with said buckle, and other buckles at the extended end of the first girdle member engageable with the extremities of the first reinforcing and equalizer strip.
